UNITED STATES PATENT OFFICE.

SIMON P. COOPER, OF CINCINNATI, OHIO.

DESIGN FOR A HAND-STAMP.

Specification forming part of Design No. 5,135, dated July 25, 1871.

To all whom it may concern:

Be it known that I, SIMON P. COOPER, of Cincinnati, in the county of Hamilton and State of Ohio, have invented and produced a new and original Design for a Printing-Stamp, of which the following is a specification:

The nature of my design is fully represented in the accompanying illustration, in which Figure 1 is a side elevation of the stamp. Fig. 2 is a plan, and Fig. 3 is an end elevation of the same.

I claim as my invention—
The design for a printing-stamp, as shown. *
In testimony of which invention I hereunto set my hand.

SIMON P. COOPER.
